UNITED STATES PATENT OFFICE.

GOTTLÖB HONOLD, OF STUTTGART, GERMANY, ASSIGNOR TO THE FIRM OF ROBERT BOSCH, OF STUTTGART, GERMANY.

CURRENT INTERRUPTER AND DISTRIBUTER FOR ELECTRICAL IGNITION APPARATUS.

1,022,241.

Specification of Letters Patent.

Patented Apr. 2, 1912.

Application filed December 11, 1909. Serial No. 532,521.

To all whom it may concern:

Be it known that I, GOTTLÖB HONOLD, engineer, a subject of the German Emperor, residing at 11-13 Hoppenlaustrasse, Stuttgart, Germany, have invented certain new and useful Improvements in and Relating to a Current Interrupter and Distributer for Electrical Ignition Apparatus; and I do hereby declare the following to be a full, clear, and exact description of the invention, such as will enable others skilled in the art to which it appertains to make and use the same.

The invention relates to an arrangement for distributing the current, particularly that of a magneto generator, to the several spark plugs of an internal combustion motor, and is characterized by the fact that the commonly employed current interrupter becomes itself a distributing element, and operates with a distributing plate to direct the current to the different plugs in proper succession.

The drawings show two exemplifications of the invention.

Figures 1 to 3 show an arrangement in which the distributor is mounted directly upon a prolongation of the armature shaft of the magneto. Figs. 4 to 6 show a somewhat modified arrangement wherein the distributor is carried by a countershaft positively driven by the armature of the magneto. Figs. 1 and 4 are front elevations with the distributing plate removed; Figs. 2 and 5 are longitudinal central sections through the distributor; and Figs. 3 and 6 show the distributing plate itself, as seen from the inner side.

In all of the figures the corresponding parts are designated by the same characters.

In both modifications one end of the armature winding is grounded, preferably by being connected to the armature shaft, and the other end of the winding is connected to a pin *a*, passing concentrically through and insulated from the armature shaft, and in conducting connection with the interrupter contact *b*, which is in each case insulated from its carrier. In the modification shown in Figs. 1 to 3 the carrier for the interrupter contact piece *b* is the disk *k* mounted directly on the armature shaft and in electric connection therewith, and the pin *a* serves the purpose of holding the contact piece *b* to the carrier. In the modification shown

in Figs. 4 to 6 the contact piece *b* is carried by a pinion *l* on a counter-shaft supported in the frame of the magneto, the pinion *l* meshing with a pinion on the shaft of the magneto as shown; and in this case the conducting connection between the pin *a* and contact piece *b* is through the intermediate contact member *c d e*, whose contact brushes *c* and *e* are concentric with the counter-shaft and the armature shaft respectively and are electrically connected by the strip *d*, mounted in the distributing plate *f* and spring-pressed inwardly as shown.

With a platinum contact point on the contact-piece *b* there coöperates a second platinum contact point on the bell crank lever *m*, which is pressed by the spring *n* into the circuit-closing position illustrated in Figs. 1 and 4, and the spring *n* is in electrical connection with the carrier, from which the contact-piece *b* is insulated, so that the two interrupter elements *b* and *m* constitute a short-circuiting device for the armature winding. The short circuit is periodically broken, in a manner which is now well known, by the cam projections on notched ring *i* which embraces the interrupter carrier, so that the projections on the ring come periodically into engagement with the bell-crank lever *m* to open the short circuit.

At the instant when the short circuit is broken the current is distributed to the proper spark plug by the arrangement which forms the particular subject matter of this invention. To this end there is set into the contact-piece *b* a spring-pressed carbon brush *g* which, during the rotation of the interrupter carrier, contacts with segmental contact-pieces *h* set into the face of the oppositely disposed distributing disk. These contact segments have conducting terminals projecting through the front face of the distributing plate and are intended for connection in the usual manner to the different spark plugs. It will be seen, therefore, that the interrupter *b-m*, short circuits the armature winding until contact is broken at the projections on the ring *i*, whereupon the current flows through brush *g* and the proper contact segment *h* to the spark-plug connected with that contact segment.

The notched cam ring *i* is mounted with

in a bore on the side plate of the magneto and is capable of a limited oscillatory movement of adjustment to vary the time of sparking in the well-known manner.

- 5 The modification shown in Figs. 1 to 3 is suitable for one or two cylinder motors; while that of Figs. 4 to 6 can be adapted to any desired number of cylinders. In the drawings, two-fold and four-fold current 10 distribution are illustrated, but other distribution may be arranged by correspondingly changing the number and location of the segments *h*, and the notches of the notched cam ring *i*.
- 15 It will be observed that while the arrangement of Figs. 1 to 3 requires a carrier disk *k* for the interrupter, in the arrangement of Figs. 4 to 6 the interrupter is carried directly by the distributing pinion *l*.
- 20 The advantage of the invention lies in the very material simplification of the apparatus, and also in the fact that both the distributor and the interrupter are made accessible by the removal of a single piece 25 of the apparatus.

Having now particularly described and ascertained the nature of my said invention and in what manner the same is to be performed, I declare that what I claim is:

- 30 1. In a current interrupter and distributor for magneto ignition apparatus, a housing containing an interrupter having a pair of interrupter elements, a cam adapted to periodically separate said elements, and a 35 contact brush carried by the interrupter, in combination with a distributing plate constituting a closure for said housing and carrying a series of contact segments adapted to successively contact with said brush; 40 substantially as described.

2. In a current interrupter and distributor for electrical ignition apparatus, an interrupter having a pair of interrupter elements, an adjustable cam adapted to periodically separate said elements, a contact 45 brush carried by the interrupter, a distributing plate having a series of contact segments adapted to successively contact with said brush, and means for adjusting said 50 cam, whereby the separation of said elements relative to the period of contact between the brush and each of said segments may be adjusted; substantially as described.

- 55 3. In a current interrupter and distributor for electrical ignition apparatus, a rotary interrupter support, two coöperating interrupter elements on said support, an adjustable cam ring embracing said elements and engaging one of them to separate 60 them periodically, a contact brush carried by the other of said elements, a distributing

plate having a series of contact segments disposed opposite to said brush and in contacting relation thereto, and an adjusting lever connected to said cam ring; substantially as described. 65

4. In a current interrupter and distributor for magneto ignition apparatus, a pinion on the shaft of the magneto, a distributor pinion meshing therewith, two coöperating 70 interrupter elements on said distributor pinion, an adjustable cam ring embracing said elements and engaging one of them to separate them periodically, a contact brush carried by the other of said elements, a distributing plate having a series of contact segments disposed opposite to said brush and in contacting relation thereto, and an adjusting lever connected to said cam ring; 75 substantially as described.

5. In a current interrupter and distributor for electrical ignition apparatus, a housing containing a rotary interrupter support, a pair of interrupter elements on said support, an adjustable cam ring embracing 80 said elements and engaging one of them periodically to separate them, and a contact brush carried by the other interrupter element, in combination with a distributing plate constituting a closure for said housing and carrying a series of contact segments disposed opposite to said contact brush in contacting relation thereto, and an adjusting lever connected to the adjustable cam ring and extending through the wall 85 of the housing; substantially as described. 90

6. In a current interrupter and distributor for magneto ignition apparatus, a housing formed on the end plate of the magneto, said housing inclosing a pinion on the shaft 100 of the armature, a distributor pinion meshing therewith, a pair of interrupter elements on the distributing pinion, an adjustable cam ring embracing the interrupter elements and engaging one of them periodically to separate them, and a contact brush carried by the other interrupter element, said housing having a cover constituting a distributing plate and carrying a series of contact segments disposed opposite to said contact brush and in contacting relation thereto, and an adjusting lever connected to the adjustable cam ring and projecting through the wall of the housing; substantially as described. 110 105

In testimony whereof I have affixed my signature, in presence of two witnesses.

GOTTLOB HONOLD.
